UNITED STATES PATENT OFFICE.

EDNA A. PERRY, OF BEVERLY, MASSACHUSETTS.

SEAM OF STITCHES FOR UNITING MATERIALS AT THEIR ABUTTING EDGES.

1,104,072.

Specification of Letters Patent.

Patented July 21, 1914.

Application filed April 14, 1909. Serial No. 489,856.

To all whom it may concern:

Be it known that I, EDNA A. PERRY, a citizen of the United States, residing at Beverly, in the county of Essex and State of Massachusetts, have invented certain new and useful Improvements in Seams of Stitches for Uniting Materials at Their Abutting Edges; and I do hereby declare the following to be a full, clear, and exact 10 description of the invention, such as will enable others skilled in the art to which it appertains to make and use the same.

The present invention relates to a seam of stitches and more particularly to a seam of 15 stitches for uniting materials at their abutting edges.

The object of the present invention is to devise a simple and durable seam of stitches which may be formed from a single thread 20 to unite materials at their abutting edges. Another object of the present invention is to provide a method of making such stitch which may be practised either by hand or by machinery.

With these objects in view the present invention consists of a seam of stitches and the method of making the same, shown in the accompanying drawings and hereinafter described and more particularly defined in 30 the claims.

In the drawings which illustrate the preferred form of the present invention, Figure 1 shows a seam of stitches formed in accordance with and embodying the present 35 invention and also illustrating the method of producing such seam; Fig. 2 is a similar view looking in the opposite direction from Fig. 1; and Fig. 3 is a cross sectional view on line 3—3, Fig. 1.

As shown in Figs. 1 and 2, the seam of 40 stitches comprises a plurality of loops 1 passed through holes 2 in the materials, adjacent their abutting edges in any suitable manner, the holes preferably being staggered with relation to each other. The loops 45 extend across the intervening material and between the abutting edges thereof, and through the ends of the loops are passed the single threads 3 which extend from one hole 50 to the other on the opposite side of the materials from the double threads of the loops, these single threads connecting alternate loops. For the sake of clearness the side 55 of the materials on which the double threads lie will be referred to as the upper

side of the materials and that upon which the single thread lies as the lower side of the materials. The method of making the stitch consists in first forming a loop and passing it upwardly through one of the materials. The next step consists in passing the free end of the thread bodily through the end of the loop, and then forming another loop and passing that upwardly through the other material; the free end of 60 the thread is then passed through the end of this loop. These operations may be repeated, loops being formed and passed upwardly through first one material and then the other, each loop being locked by the free 65 end of the thread which is passed through it before the next succeeding loop is formed. The seam of stitches thus produced, as shown in Fig. 1, is similar to what is commonly known as the "base ball" stitch, so 70 called from its general use in uniting the covers of base balls, except that in the present stitch double threads are seen upon what is referred to as the upper side of the material instead of a single thread as in the old 75 and well known stitch above referred to.

The stitch forming the subject of the present invention possesses many advantages, however, over the old base ball stitch. In the first place, it is a locked stitch so that, 80 although the thread may break or give way at one or more points, the seam as a whole will still hold effectively. Again, if the side of the seam having the double threads be the exposed side which, of course, in a base ball 85 would be the outside of the cover, the wearing qualities of the seam are greatly increased since there are two threads to take the wear instead of a single thread as in the old stitch.

Where in the claims the word "upwardly" 90 is used, it is to be understood simply as designating relative and not absolute direction, as the seam may be so sewn as to leave either the single or the double threads exposed. Although in the drawings the stitch is shown as having the ends of the loops carried down between the abutting edges of the materials, the present invention, except 95 where so specially defined in the claims, is not limited to such a construction, as the position of the end of the loop obviously depends upon the length of the loop, and a longer or shorter loop may be employed as 100 desired.

Having thus described the invention, what is claimed as new, is:—

1. In a seam of stitches for uniting materials at their abutting edges with a single thread the combination with the materials having abutting edges to be sewn, of loops of thread on one side of the materials arranged alternately first upon one material and then upon the other, and single threads 10 connecting the loops on the opposite side of the materials, each single thread passing through the closed end of one of said loops, substantially as described.

2. In a seam of stitches for uniting materials at their abutting edges with a single thread the combination with the materials having abutting edges to be sewn, of loops of thread on one side of the materials extending to the abutting edges of the materials alternately first from one material and then from the other, and single threads 20 on the opposite side of the materials extending across the abutting edges from one material to the other and connecting the alternate loops, each single thread passing through the closed end of one of said loops, substantially as described.

3. In a seam of stitches for uniting materials at their abutting edges the combination with the materials having abutting edges to be sewn, of a plurality of loops of thread, each loop of which is passed upwardly through a single one of a series of holes disposed in a single row in each of the respective materials adjacent to the abutting edges, extends along the surface of the material from said hole to the abutting edges and is held by thread passed through its closed end at the abutting edges, substantially as described.

4. In a seam of stitches for uniting materials at their abutting edges the combination with the materials having abutting edges to be sewn, of loops of thread passed 45 upwardly through holes disposed in a single row in each of the respective materials adjacent to the abutting edges, extending along the upper surface of the materials from said holes to the abutting edges and secured by thread extending beneath the materials and passed through the closed ends of the loops at the abutting edges, substantially as described.

5. In a seam of stitches for uniting ma-

terials at their abutting edges the combination with the materials having abutting edges to be sewn, of loops of thread passed upwardly through holes in each of the materials adjacent to the abutting edges, extending along the surface of the materials from 60 said holes to the abutting edges and held by a thread from the other side of the materials passed through the closed ends of the loops at the abutting edges of the materials, substantially as described. 65

6. In a seam of stitches for uniting materials at their abutting edges the combination with the materials having abutting edges to be sewn, of loops of thread passed upwardly through holes disposed in a single row in each of the respective materials adjacent to the abutting edges, extending along the surface of the materials from 70 said holes to the abutting edges and held by a thread from the other side of the materials 75 passed through their closed ends at the abutting edges, substantially as described.

7. In a seam of stitches for uniting materials at their abutting edges the combination with the materials having abutting edges to be sewn, of loops of thread passed upwardly through a single series of holes in each of the pieces of materials located in staggered position with relation to each other adjacent to the abutting edges, extending along the surface of the materials from 80 said holes to the abutting edges and held by a thread from the other side of the materials 85 passed through their closed ends at the abutting edges, substantially as described. 90

8. In a seam of stitches for uniting materials at their abutting edges the combination with the materials having abutting edges to be sewn, of loops of thread passed upwardly through holes disposed in a single 95 row in each of the respective materials adjacent to the abutting edges, extending along the surface of the materials from said holes to the abutting edges and held by single threads passed through their closed ends at 100 the abutting edges, substantially as described.

In testimony whereof I affix my signature, in presence of two witnesses.

EDNA A. PERRY.
